DESIGN FOR A TEXTILE FABRIC

George Bischof, Union City, N. J.

Application July 7, 1938, Serial No. 78,332

Term of patent 3½ years

To all whom it may concern:

Be it known that I, George Bischof, a citizen of the United States and a resident of the city of Union City, in the county of Hudson and State of New Jersey, have invented a new, original, and ornamental Design for a Textile Fabric, of which the following is a specification, reference being had to the accompanying drawing constituting a part thereof.

The figure is a plan view of a piece of the fabric showing my new design.

I claim:

The ornamental design for a textile fabric, substantially as shown.

GEORGE BISCHOF.
